UNITED STATES PATENT OFFICE.

CARL REIFFEL, OF CHICAGO, ILLINOIS.

MUSICAL INSTRUMENT.

Application filed May 4, 1922. Serial No. 558,403.

To all whom it may concern:

Be it known that I, CARL REIFFEL, a citizen of the United States of America, and a resident of Chicago, county of Cook, and State of Illinois, have invented a new and useful Improvement in Musical Instruments, of which the following is a specification.

This invention relates to musical instruments of the horn class, wherein a slide is used for obtaining the variable notes.

The main objects of this invention are to provide a horn of the above character producing a fundamental note and having an improved form of slide attachment for varying the length of the vibrating column of air within the horn for producing the different notes within the range of the instrument; and to provide improved means for supporting the slide on the horn.

An illustrative embodiment of this invention is shown in the accompanying drawings, wherein—

Figure 1 is a front elevation of a horn embodying this invention.

Fig. 2 is a view partly in plan and partly in side elevation and taken on the line 2—2 of Figure 1.

Fig. 3 is a transverse section taken on the line 3—3 of Figure 2.

Fig. 4 is a detail in section, showing the means for detachably connecting the slide and operating handle.

Fig. 5 is a section taken on the line 5—5 of Fig. 4.

In the form shown, the present invention is applied to a tapered horn including the usual mouthpiece for producing the fundamental note. The air column within the horn serves as a resonating medium for the sound produced by the mouthpiece, as is well understood in the art, and the pitch of the horn depends almost exclusively on the length of the air column set in vibration. Variable notes are obtained by varying the length of the vibrating column of air within the horn. For this purpose, the horn is provided with a series of lateral openings arranged to provide communication between the vibrating column of air within the horn and the ambient air. In horns having a uniform bore, the lateral openings should also be of uniform size, but in horns having a tapered bore, the lateral openings should be of progressively increasing size in proportion to the bore

of the horn at the openings, in order to avoid deepening or deadening the tone of the notes.

The successive opening and closing of the lateral openings, for obtaining any note within the range of the instrument, is controlled by means of a slide which is arranged within a tubular casing mounted on the exterior of the instrument.

Referring to the drawings, the instrument comprises a tapered horn 1 having the usual mouthpiece 2 and flared end 3. Mounted on the neck of the horn adjacent the mouthpiece, is a pair of octave keys 4 of usual construction.

Formed in the front wall of the horn, is a series of openings 5 arranged in a row extending longitudinally of the horn and progressively increasing in size in proportion to the tapered bore opposite the respective openings.

Rigidly mounted on the exterior of the horn adjacent the lateral openings 5, is a cylindrical casing 6, open at both ends and having two rows of oppositely disposed openings 7, which are arranged in register with, and of the same size as, the openings 5 of the horn. Communication through the openings 5 and 7 between the interior and exterior of the horn is controlled by a cylindrical slide 8, which fits snugly within the casing 6, and which is longitudinally shiftable within said casing across the openings 7 by means of an operating handle 9.

The operating handle 9 is in the form of a U-shaped squared shaft having a cylindrical head 14 threaded on the upper end thereof and adapted to fit snugly within a bushing 15 secured within the cylindrical slide 8 adjacent its lower end. Mounted on the cylindrical head 14 of the operating handle, are diametrically opposed pins 10 for engagement with bayonet slots 11 formed in the bushing 15. The other end of the handle is bent to form a finger grip 12. The operating handle extends through guides in the form of lugs 13 mounted on the exterior of the horn and coacting with the squared shaft to secure the piston slide 8 against turning in the cylindrical casing 6. When the instrument is not in use, the slide 8 may be removed from the handle and the latter telescoped within the cylindrical casing 6, or if desired, the handle may be removed from the instrument. To remove the handle 9 from the instrument, the slide

8 is shifted upwardly sufficiently to permit its upper end to be grasped in the fingers and turned to disengage the pins 10 from the bayonet slots 11. The head 14 may then 5 be unscrewed from the handle 9 to permit the latter to be withdrawn through the lugs 13.

In operation, the variable notes are obtained by moving the slide 8 through the top 10 of the casing 6, so as to permit the air to pass through the openings 5 and 7 below the piston. The octave in which the instrument is played is controlled by the keys 4.

Although but one specific embodiment of 15 this invention has been herein shown and described, it will be understood that certain details of the construction shown may be altered or omitted without departing from the spirit of this invention as defined by the 20 following claims.

I claim:

1. A musical instrument of the class described comprising a horn adapted for producing a fundamental note and having a 25 series of lateral openings formed therein, a tubular casing arranged on the exterior of said horn and having a series of openings located adjacent said lateral openings, and a slide mounted in said tubular casing and 30 being longitudinally shiftable for successively opening and closing communication through said openings between the interior and exterior of the horn.

2. A musical instrument of the class described comprising a horn adapted for producing a fundamental note and having a 35 series of lateral openings formed therein, a cylinder mounted on the exterior of said horn and having a series of openings registering with said lateral openings, a piston 40 mounted in said cylinder and arranged for successively opening and closing communication through said openings between the interior and exterior of the horn, and an operating handle detachably secured to one 45 end of said piston.

3. A musical instrument of the class described comprising a horn adapted for pro-

ducing a fundamental note and having a series of lateral openings formed therein, a 50 cylinder mounted on the exterior of said horn and having a series of openings registering with said lateral openings, a piston mounted in said cylinder and arranged for successively opening and closing communication 55 through said openings between the interior and exterior of the horn, an operating handle including a squared shaft detachably secured to one end of said piston, and a guide mounted on said horn and coacting 60 with said shaft for securing said piston against rotation relative to said cylinder.

4. A musical instrument of the class described comprising a horn including a mouthpiece and having a bore tapering from 65 the mouthpiece, said horn having a series of lateral openings formed therein and arranged in a row extending longitudinally thereof, said openings progressively increasing in size in proportion to the bore of 70 the horn at said openings, a cylinder mounted on the exterior of the horn and having a series of openings registering with said lateral openings, each of the registering openings being of the same size, and a piston 75 arranged in said cylinder for successively opening and closing communication through said openings between the interior and exterior of the horn.

5. A musical instrument of the class described comprising a horn adapted for producing a fundamental note and having a series of lateral openings formed therein, a cylinder mounted on the exterior of said horn and having a series of openings registering with said lateral openings, a piston mounted in said cylinder and arranged for successively opening and closing communication 80 through said openings between the interior and exterior of the horn, and an operating handle detachably secured to one end of said piston, said horn and operating handle having coacting shoulders for securing 85 said handle and piston against turning.

Signed at Chicago this 1 day of May, 1922.

CARL REIFFEL
